UNITED STATES PATENT OFFICE.

WEBB JAY, OF CHICAGO, ILLINOIS.

LIQUID-ELEVATING DEVICE.

1,180,925.

Specification of Letters Patent. Patented Apr. 25, 1916.

Application filed November 15, 1915. Serial No. 61,476.

To all whom it may concern:

Be it known that I, WEBB JAY, a citizen of the United States, residing at Chicago, in the county of Cook and State of Illinois, have invented new and useful Improvements in Liquid-Elevating Devices, of which the following is a specification, reference being had to the accompanying drawings, forming a part thereof.

10 This invention relates to apparatus for lifting liquid from a lower to a higher receptacle by suction, the particular details being designed with special reference to the use of the device on a motor vehicle, as for 15 lifting liquid fuel from a low level tank to a position from which it may be supplied by gravity to the carburetor of the vehicle motor.

20 The various elements comprising the present structure are similar to the elements shown in my co-pending application, Serial No. 39,943, filed July 15, 1915, but the present invention involves a different arrangement of said elements and certain resultant 25 modification of detail hereinafter described and shown in the drawing, as indicated by the claims.

30 In the drawings: Figure 1 is a diagrammatic side elevation indicating the relative location of the several parts of this invention upon the motor vehicle. Fig. 2 is a fore-and-aft vertical section of the principal elements of the invention.

35 Referring first to Fig. 1, the main supply tank is indicated at A, disposed as frequently at the rear of the vehicle, the general outline of said vehicle being presented in dotted lines. The remainder of the apparatus is disposed alongside the engine under the hood 40 or bonnet inclosing the same and is connected with the tank, A, by a single pipe, B, which terminates in the tank near the bottom thereof and is arranged to empty into a receiving chamber, 1. Through a duct 45 or conduit, 2, formed in a common head or cover, 3, the chamber, 1, is placed constantly in communication with an air inlet chamber, 4, from which a pipe, C, leads to a source of suction as for example, the intake manifold of the engine as indicated in Fig. 1. Through the agency of the suction acting through the pipe, C, and small aperture, 5, through which said pipe communicates with the chamber, 4, the pressure in the latter 50 chamber and in the chamber, 1, is so reduced as to cause the atmospheric pressure acting

upon the liquid in the tank, A, to force said liquid through the pipe, B, and into the chamber, 1. The drain, 6, controlled by a valve, 7, opening into an atmospheric pressure chamber, 8, serves at certain times for the discharge of the liquid accumulated in the receiving chamber, 1. But, since the chamber, 8, is at all times under atmospheric pressure acting through its constantly open 60 vent, 8^a, the valve, 7, cannot open to discharge the liquid in the chamber, 1, so long as the chamber, 1, is subject to the suction through the pipe, C, and the resulting reduced pressure. Said chamber, 1, therefore 70 continues to fill until it over-flows through the conduit, 2, into a receiving cup, 9, carried on the end of a lever, 10, whose opposite end controls an air valve, 11, having a port, 12, which is large as compared with 75 the aperture, 5. The forked end, 10^a, of the lever, 10, engages the stem of the valve, 11, with lost motion, operating between and upon shoulders, 11^a and 11^b, the latter of which limits the movement of the lever, 10, 80 in one direction while the cup, 9, stops against the bottom of the air inlet chamber, 4, to limit the movement in the opposite direction. The lever, 10, is yieldingly held at either of said limits in a readily understood manner by means of a spring or springs, 13, connecting a point on the lever with a point on its supporting bracket, 14, at the opposite side of its fulcrum, 15. Thus, 85 as the overflowing liquid from the chamber, 1, accumulates in the cup, 9, and increases its weight, the lever, 10, is swung to a position for opening the air valve, 11, whereupon by reason of the comparatively large area of the port, 12, the effect of suction 90 through the pipe, C, is practically nullified and the liquid ceases to be drawn any longer from the tank, A. The cup, 9, however, is provided with a leak aperture, 9^a, through which the liquid gradually escapes into the 95 chamber, 4 and thence into a drain, 16, similar to the drain, 6, and provided with a similar valve, 17, which is contained within the valve chamber, 18, into which it opens, 100 said valve chamber constituting substantially the receiving end of, and opening into a pipe, 19, leading to the carburetor float chamber, D, indicated on Fig. 1, for furnishing the liquid fuel to said carburetor 105 and a branch pipe, 20, leads from the atmospheric pressure chamber, 8, into said pipe, 19. Through the branch, 20, the chamber, 110

bers, 8 and 18, are placed in constant communication both delivering the liquid to the pipe, 19, and thence to the carbureter, and both being exposed to atmospheric pressure, 5 the chamber 8, continuously through the vent, 8^a, and the valve chamber, 18, intermittently through the atmosphere port, 12, so that both of said chambers are subject 10 to atmospheric pressure by way of the vent, 8^a. Thus it will be seen that upon the opening of the air valve, 11, which restores atmospheric pressure to the chambers, 4 and 1, the liquid contents of the chamber, 1, will immediately be discharged into the chamber, 15 8, there being no longer any suction to hold the valve, 7, closed, and for a similar reason the liquid discharged through the leak, 9^a, and the cup, 9, will drain at once into the chamber, 18.

20 As the quantity of liquid in the cup, 9, decreases, the weight of the opposite end of the lever, 10, will begin to over-balance the cup and eventually the lever will return to the position in which it is illustrated in 25 Fig. 2, and immediately upon such return by closing the valve, 11, will again subject the chamber, 4, to the suction through the pipe, C and the cycle of operation will be repeated.

30 It will be understood that all the liquid discharged into the chamber, 8, becomes immediately available for use in the carbureter at a rate determined by the demand of the engine and controlled by the usual 35 float-operated valve in the chamber, D, of said carbureter and the liquid discharged into the chamber, 18, is similarly available during the time the valve, 11, is open. Obviously, in order to prove adequate at any 40 time to the maximum demand of the engine for fuel, the liquid feeding apparatus above described should be capable of supplying the fuel at a rate somewhat in excess of the ordinary normal demand, and from this it 45 follows that under ordinary running conditions, and especially under unusually favorable running conditions, the engine will consume the fuel through its carbureter at a slower rate than such fuel is delivered to 50 the chambers, 8 and 18, by the feeding mechanism. Thus, after the mechanism has operated through a few cycles, it will accumulate a surplus of liquid tending to completely fill the chambers, 8 and 18, with 55 their pipes, 19 and 20, leading to the carbureter. Successive discharges from the chamber, 1, to the chamber, 8, will gradually raise the general level of liquid in said 60 chambers, 8 and 18, so that in the event of a long continued low demand of the engine for fuel, the liquid will rise to such a point in the chamber, 4, that the cup, 9, when filled by the overflow from the chamber, 1, and descending so as to open the 65 valve, 11 will dip into liquid so deep that

said cup will not empty through its leak-port, 9^a, sufficiently to cause the reverse action for closing said valve, 11 until the level of liquid in the chamber, 4, has sufficiently subsided. Thus the air valve, 11, 70 will remain open until the engine has used up enough of the surplus to practically empty the chamber, 4, and the suction through the pipe, C, will not operate until the reserve supply of liquid fuel is thus 75 diminished.

The blockade of the action of the lever-carried cup, 9, for operating the valve, 11, will always occur when the valve, 11, is open and never when it is closed because 80 the change of level of liquid in the chamber, 4, occurs almost entirely while the cup is down, because the entire contents down to the level of the liquid in the chamber, 4, is discharged while the cup is down, whereas all that is discharged while the cup is up consists of a few drops which can trickle out through the port, 9^a, during the instant occupied in filling the cup by the deluge delivered to the relatively large duct, 2; and the change of level in said chamber, 4, occurring between the time when the cup having been depressed is able to empty sufficiently to cause it to rise again, and the time it is next depressed, will be very small 95 in comparison with the quantity which it will discharge at said next depression, and also small in comparison with the quantity which can be contained in said chamber in so much of its depth as the distance to 100 which the cup is depressed in the liquid by the reaction of the spring, 13.

I claim:—

1. In combination with a main low level reservoir, a receiving chamber at a higher level; a conduit from the main reservoir discharging into the receiving chamber; an air inlet chamber at approximately the level of the receiving chamber having a suction connection and an atmosphere port; a suction and overflow connection from the upper part of the receiving chamber to the upper part of said air inlet chamber; a valve controlling the atmosphere port; a device movably mounted in the air inlet chamber adapted and positioned to be moved by the discharge and accumulation of liquid from said overflow connection; means operatively connecting said device to the atmosphere inlet valve, an atmospheric pressure chamber into which the receiving chamber discharges by gravity; a valve which is opened by such gravity discharge and is adapted to be seated by suction from the receiving chamber, a valve chamber into which the air-inlet chamber discharges by gravity, a valve in said chamber which is opened by such gravity discharge and is adapted to be seated by suction from the air inlet chamber, and a liquid conduit lead- 115 120 125

ing from the atmospheric pressure chamber and from said valve chamber for delivering the contents of both said chambers to the same destination.

- 5 2. In combination with a main low level reservoir, a receiving chamber at a higher level; a conduit from the main reservoir discharging into the receiving chamber; an air inlet chamber at approximately the level of 10 the receiving chamber having a suction connection and an atmosphere port and a valve controlling said port; a suction and overflow connection from the receiving chamber to the air inlet chamber opening for discharge 15 in the air inlet chamber at the upper part thereof; a device movably mounted in said air inlet chamber, comprising a liquid receiver positioned for receiving the liquid discharged through said overflow and adapted 20 to be moved by the weight of the liquid so received, and means operatively connecting said device with the atmosphere valve for opening the latter by said movement, said receiver having a leak port through 25 which the accumulated liquid is adapted to drain slowly in comparison with the rate at which it may be filled by the overflow; a valve chamber into which said air inlet chamber drains; a valve in said chamber 30 controlling such drainage adapted to be opened by gravity flow into the valve chamber, and to be seated by suction from the air inlet chamber, and a liquid service pipe leading from said valve chamber for supplying 35 a device adapted to utilize the liquid.
3. In combination with a main low level reservoir, a receiving chamber at a higher level; a conduit from the main reservoir discharging into the receiving chamber; a device positioned lower than said receiving chamber and adapted to utilize the liquid which may be received into and discharged from said receiving chamber; an air inlet chamber positioned alongside said receiving 40 chamber, having a suction connection and an atmosphere port and a valve controlling said port; a common cover for said receiving chamber and said air inlet chamber whereby they are associated as a unit, said cover containing 45 a suction and overflow conduit between the two chambers; a device movably

mounted in the air inlet chamber comprising a receiver positioned under the discharge end of the overflow conduit from the receiving chamber into the air inlet chamber and 55 adapted to be moved by the weight of the liquid thus received for opening the atmosphere valve; a valve chamber into which the air inlet chamber discharges by gravity; a valve in said valve chamber which is opened 60 by such gravity discharge and is adapted to be seated by suction from the air inlet chamber, and a service pipe from said valve chamber to the device which utilizes the liquid. 65

4. In combination with a main low level reservoir, a receiving chamber at a higher level; a conduit from the main reservoir discharging into the receiving chamber; an air inlet chamber at approximately the level of 70 the receiving chamber having a suction connection and an atmosphere port and a valve controlling said port; a suction and overflow connection from the upper part of the receiving chamber to the upper part of the 75 air inlet chamber; a device movably mounted in said air inlet chamber comprising a receiver positioned for receiving the liquid discharged from the overflow conduit, and adapted to be moved by the accumulation of 80 such liquid for opening the atmosphere valve, and being provided with means for slowly emptying said receiver of the liquid so received for operating it, and means for reversing its movement for closing the 85 atmosphere valve when it is thus emptied; a device adapted to utilize the liquid; drainage discharge connections from the bottom of the receiving chamber and air inlet chamber respectively; valves adapted to be opened 90 by gravity discharge from said chambers and to be seated by suction from said chambers respectively; and a conduit from the device which utilizes the liquid having connections at its upper end for receiving the 95 liquid discharged by gravity from said receiving chamber and said air inlet chamber respectively.

In testimony whereof, I have hereunto set my hand, at Chicago, Illinois, this 8th day of November, 1915. 100

WEBB JAY.
